WITNESSES:

UNITED STATES PATENT OFFICE.

MIKE PAVLICA, OF SHINGLETION, MICHIGAN.

NONREFILLABLE BOTTLE.

1,411,179.

Specification of Letters Patent. Patented Mar. 28, 1922.

Application filed December 12, 1921. Serial No. 521,707.

To all whom it may concern:

Be it known that I, MIKE PAVLICA, residing at Shingleton, in the county of Alger and State of Michigan, have invented new and useful Improvements in Nonrefillable Bottles, of which the following is a specification.

My present invention has reference to bottles, and has for its object to provide a bottle which means whereby the contents thereof cannot be removed and the bottle refilled with inferior liquids without detection.

The foregoing and other objects which will appear as the nature of the invention is better understood, may be accomplished by a construction, combination and operative association of parts, such as is disclosed by the drawings which accompany and which form part of this specification.

In the drawings:—

Figure 1 is an approximately vertical central sectional view through a bottle in accordance with this invention.

Figure 2 is a similar view showing the cork rearranged in the collar in the bottle neck after the same has been withdrawn therefrom.

Figure 3 is a sectional view on the line 3—3 of Figure 1.

Figure 4 is an approximately central vertical sectional view through the collar.

Figure 5 is a similar view through the bottle neck.

Referring now to the drawings in detail, the numeral 1 designates a portion of an ordinary bottle, the same being provided with the usual restricted neck 2. Between the neck and bottle proper there is a flange 3, and the inner wall of the neck at desired spaced intervals is provided with longitudinally disposed depressed portions 4 whose inner walls preferably are arranged at an inward inclination from the flange or shoulder 3 and whose upper or outer walls are straight.

In the neck, and resting on the shoulder provided by the flange 3 there is a tubular member in the nature of a collar 5. Preferably the collar is constructed of brass and has both the wall of its bore and its outer periphery provided at spaced intervals with longitudinally arranged depressions 6 and

7 respectively that provide pockets for flat springs 8 and 9 respectively. The outer and inner series of springs 8 and 9 are arranged in pairs which are disposed opposite each other and which are connected together and secured to the collar by means of pins 10 which pass through the collar adjacent to the inner end thereof. When the collar is received in the bottle neck the outer springs 8 will leave the pockets provided by the depressions 6 and enter the depressions 4, the outer ends of the said springs contacting with the straight upper or outer shoulders provided by the depressions 4, and thus effectively secure the collar in the bottle neck. The inner springs 9 are designed to engage a cork or similar stopper 11. As the springs 9 exert an inward tension angularly with respect to the stopper, it will be apparent that the stopper 11 cannot be forced through the passage 12 in the flange 3 in the body of the bottle, and it will also be apparent that by the employment of a cork screw the stopper 11 may be withdrawn. When withdrawn, the stopper will have its inner end resting on the upper ends of the inner springs 9, when the said stopper is reinserted in the collar to temporarily seal the bottle. Before the collar is inserted in the bottle neck, the stopper 11 is forced into the bore of the collar from the inner end thereof, and it is thought that the foregoing description, when taken in connection with the drawings will fully set forth the construction and advantages of the improvement to those skilled in the art to which this invention relates.

The stopper 11 is of a greater length than collar, as the said stopper is received in the opening 12 of the flange 3 in the neck of the bottle when the bottle is sealed.

Having described the invention, I claim:—

A bottle having an inwardly directed flange at the juncture of the neck and body thereof and said neck having its inner surface provided with longitudinally arranged depressions whose inner walls are arranged at an inward angle from the flange, a collar designed to be inserted in the bottle neck and to rest on the flange, said collar having its inner and outer surface provided with longitudinal depressions, flat springs ar-

ranged in opposed pairs designed to be seated in the depressions, means passing through the collar, adjacent to the inner end thereof and securing the springs thereon, the outer springs designed to engage in the depressions in the bottle neck and to have their ends contact with the outer

end walls in the said depressions, and a stopper inserted from the inner end of the collar and engaged by the inner springs on said collar.

In testimony whereof I affix my signature.

MIKE PAVLICA.
